UNITED STATES PATENT OFFICE.

EVERETT J. COOK, OF TOLEDO, OHIO, ASSIGNOR TO THE DURA COMPANY, OF TOLEDO,
OHIO, A CORPORATION OF DELAWARE.

WINDOW-CONTROL MECHANISM.

Application filed February 12, 1923. Serial No. 618,735.

To all whom it may concern:

Be it known that I, EVERETT J. COOK, a citizen of the United States of America, residing at Toledo, in the county of Lucas and 5 State of Ohio, have invented certain new and useful Improvements in Window-Control Mechanism, of which the following is a specification, reference being had therein to the accompanying drawings.

10 This invention relates to window control mechanisms and particularly relates to actuating devices for the sliding windows of motor vehicles.

The invention consists in the structural 15 features and arrangement of parts herein-after described and illustrated in the accompanying drawings, wherein:

Figure 1 is a view in interior elevation of 20 an automobile door equipped with the improved control mechanism;

Figure 2 is a similar view of the mechanism in a modified form;

Figure 3 is a vertical section on line 3—3 of Figure 1;

25 Figure 4 is a perspective view showing the mounting of the actuating element for the mechanism and the latch means for the same;

Figure 5 is an enlarged view of a portion 30 of Figure 3.

In these views the reference character 1 designates an automobile door having in its upper portion a window opening 2 and having as a closure for said opening a vertically 35 slideable glass plate 3 adapted in lowered position to enter a chamber 3^a formed in the lower portion of the door. To the lower edge of the plate 3 there is secured the usual sheet metal channel strip 4 embracing said 40 plate. 5 is a sheet metal channel member rigidly depending from the strip 4, the opening of said channel being toward the interior face of the door. 6 is a roller engaging in the channel 5 and carried jointly by 45 the pivotally connected ends of the two arms 7 and 8. The other ends of said arms are pivoted respectively at 7^a and 8^a to levers 9 and 10 downwardly extending within the chamber 3^a and pivotally connected adjacent 50 their lower ends, as indicated at 11. The lever 10 at its upper end carries a roller 12 which engages in a runway formed by a channel bar 13 extending substantially along the lower margin of the window opening 2 and terminally rigidly secured to the up-

rights of the door 1, said channel bar opening toward the exterior side of said door. The lever 9 is pivoted at its upper end upon a bracket 14 rigidly depending from the central portion of the runway 13. Upon 60 the mounting pin 15 for the roller 12 there is also mounted a pivotal bell crank member having the upstanding arm 16 carrying a handle 17 and having the arm 16' extending within the channel bar 13 longitudinally 65 thereof. 18 is a V-shaped spring intermediately mounted upon the arm 16' and embracing the transversely bent end 18' of said arm. The ends of said spring diverge somewhat beyond the bent extremity of the arm 70 16' so as to bear respectively upon the upper and lower flanges of the channel bar 13, thus tending to maintain the arm 16' horizontal. The upper flange of said bar is longitudinally slotted, as indicated at 19, and the 75 arm 16 projects through said slot so as to carry the handle 17 within the window opening 2. A tooth 20 projects downwardly from the bell crank 16, 16' at the juncture 80 of the arms thereof to engage a latch rack 21 formed as an upward projection upon the lower flange of the channel bar 13 (see Figure 4). 21' is a bar connecting the uprights 85 of the door 1 within the chamber 3^a and passing between the lower portions of the levers 9 and 10 below the pivot 11 thereof and 22 is a coiled spring extending from the pivotally connected ends of said levers to a bracket 23 carried by the end of the bar 21' 90 nearest adjacent to said levers.

In the operation of the described device, when the handle 17 is in its right hand limiting position, as shown in full lines in Figure 1, the glass 3 is fully raised, closing the opening 2. As the handle 17 is moved to 95 the left, the arms 7 and 8 are swung downwardly assuming the dash line position shown in Figure 1 at 7' and 8' when the levers 9 and 10 are adjusted, as indicated at 9' and 10'. When the handle 17 has been 100 shifted to a point substantially midway between the sides of the window opening, the fully lowered position of the closure 3 is established, the corresponding position of the arms 7 and 8 being indicated in dotted 105 lines at 7'' and 8'', the levers 9 and 10 being then disposed as indicated at 9'' and 10''. The downward angular movement of the arms 7 and 8 resulting from actuation of the lever 10 to the left as disclosed follows 110

primarily from the fact that the distance of the pivot 8^a exceeds, to a predetermined extent, the distance of the pivot 7^a from the joint 11 of the levers 7 and 8. Thus, as the 5 lever 10 moves into registering relation with the lever 9, the pivot 8^a is being moved to a position above the pivot 7^a. When the two pivots are so disposed the arms 7 and 8 project directly toward the left hand up- 10 right of the door occupying the intermediate position shown in dash line. As the lever 10 is actuated to the left of the lever 9 the arms 7 and 8 are swung downwardly from their 15 positions 7' and 8' to their fully lowered positions 7'', 8''.

It will be noted that the tension of the spring 22 is a minimum when the closure 3 is raised and a maximum in the fully lowered position of the closure. The movement 20 of the window responsive to the handle is most rapid between the intermediate and fully lowered position of the window and between said position the maximum counter- 25 balancing effect is exerted by the spring 22. Owing to this relation between tensioning of the spring and the varying speed of actuation of the window the pressure required to 30 actuate the closure between the limiting positions is substantially uniform. Furthermore the relatively large travel of the handle with respect to the resulting movement of 35 the closure when the latter is adjacent its raised position gives to the operator a leverage favorable for firmly engaging the weather strips 24 and 25 which are respectively carried by the lower edge portion of the closure and by the frame of the door. Engagement 40 of the tooth 20 with the rack 21 serves to firmly maintain any position of adjustment of the closure and release of the mechanism 45 is readily accomplished by rocking the bell crank 16, 16' sufficiently to raise the tooth 20 clear of said rack.

Among the advantages of the described 50 construction may be mentioned the fact that there is avoided any inwardly protruding handle or crank element and also the fact that the arms 7 and 8 and levers 9 and 10, which primarily comprise the mechanism 55 may be cheaply formed of stripped steel by punch press operations and are adapted for connection by punch press riveting.

In the construction shown in Figure 2, the 60 levers 9 and 10 are pivotally connected at 55 their lower ends, instead of projecting below the pivotal connection as in Figure 1. The construction shown in Figure 2 is adapted to be removed upwardly from the chamber 3^a after the bar 21' has been unfastened from the uprights of the door. The construction 65 shown in Figure 1 permits removal of the mechanism without disturbing the bar 21'.

What I claim as my invention is:—

1. In a window control mechanism, the 65 combination with a sliding closure, of a pair

of arms for actuating said closure having pivotally connected ends engaging the closure and slidable thereupon transverse to the sliding movement thereof, pivotal supports for the other ends of said arms, and means 70 for adjusting said supports to and from each other to swing said arms in unison and thereby actuate sliding travel of the closure.

2. In a window control mechanism, the combination with a sliding closure, of a pair 75 of arms having pivotally connected ends engaging said closure and slidable thereupon transversely to the travel thereof, a lever mounted to swing transversely to the direction of travel of the closure about a fixed pivot, and a second lever constrained at one end to a travel transverse to that of said closure and pivoted to the first mentioned lever, said arms being respectively pivoted intermediately to said levers. 80

3. In a window control mechanism, the combination with a sliding closure, of a pair 85 of pivotally connected arms engaging the closure to actuate the same and slidable upon the closure transversely to its travel, and a 90 pair of levers respectively pivotally carrying said arms, said arms being angularly actuable substantially in the direction of movement of the closure by said levers.

4. In a window control mechanism, the 95 combination with a sliding closure, of a pair of pivotally connected arms engaged with said closure at their point of pivotal connection and having said point slidable upon the closure transversely to the travel thereof, a pair of pivotally connected levers respectively intermediately carrying said arms, a fixed pivotal support for one of said levers, and an actuating member carried by the other lever and constrained to a travel 100 transverse to that of the closure. 105

5. In a window control mechanism, the combination with a sliding closure, of a pair 110 of pivotally connected arms having actuating engagement with said closure at their point of pivotal connection, said point being movable transversely of the closure, a pair of levers respectively intermediately carrying said arms, said levers having corresponding ends pivotally connected, a pivotal mounting for the other end of one of said levers, and an actuating handle and latch element carried by the other end of the other lever. 115

6. In a window control mechanism, the combination with a sliding closure, of a pair 120 of pivotally connected arms having actuating connection with said closure at their point of pivotal connection, a pair of pivotally connected levers intermediately carrying said arms, a stationary pivotal support 125 for one of said levers, actuating means carried by the other lever, and latch means for holding the said mechanism in adjustment.

7. In a window control mechanism, the combination with a sliding closure, of an 130

angularly movable lever for actuating said closure, a runway constraining one end of said lever to a rectilinear travel, a rack carried by said runway, a combined handle and 5 latch member pivotally carried by the lever, said latch member being engageable with the rack, said combined member being rockable to disengage the latch member from the rack, and a spring carried by said latch 10 member reacting upon the runway to normally engage the latch member with the rack.

8. In a window control mechanism, the combination with a sliding closure, of an 15 actuating lever therefor, a channel shaped runway extending transversely to the travel of the window member, means carried by said lever engaging in said runway to constrain said end to rectilinear travel, a latch 20 element within said runway, and an actuating element for said latch member and lever projecting through a slot in said runway into the window opening.

9. In a window control mechanism, a sliding closure, a pair of pivotally connected 25 arms having actuating engagement with the closure at their point of pivotal connection, a pair of pivotally connected levers respectively pivotally carrying said arms, a fixed pivotal support for one of said levers, an 30 actuating element carried by the other lever, and a spring acting upon said levers at their pivotal connection to counter-balance the closure.

10. In a window control mechanism, the 35 combination with a sliding closure, of an actuating mechanism therefor comprising a pair of levers having corresponding ends pivotally connected, a stationary pivot for the other end of one of said levers, and 40 guide means engaging the other end of the other lever, and a bar engaging between said levers adjacent their pivoted ends to prevent rattling of the levers.

In testimony whereof I affix my signature.
EVERETT J. COOK.
